UNITED STATES PATENT OFFICE.

JOHN CAMPBELL, OF ALLEGHENY CITY, PENNSYLVANIA, ASSIGNOR TO THE CAMPBELL DESULPHURIZING COMPANY, OF NEW YORK, N. Y.

ROASTING OR RENOVATING FURNACE.

SPECIFICATION forming part of Letters Patent No. 255,592, dated March 28, 1882.

Application filed May 5, 1881. (No model.)

To all whom it may concern:

Be it known that I, JOHN CAMPBELL, of Allegheny City, Allegheny county, Pennsylvania, have invented certain new and useful Improvements in Roasting or Renovating Furnaces, of which the following is a specification.

My invention applies to furnaces for roasting or desulphurizing ores, or for renovating bone-black or similar materials, in which the granulated material to be purified is showered down a vertical shaft through which flame rises to burn out or dissipate the consumable or volatile impurities therefrom.

My present invention is partly an improvement on a furnace of similar character on which an application was filed August 11, 1880; and it consists partly in a peculiar form of shaft which secures an agitated zigzag passage of the falling ore, and a similar zigzag reverberating passage of the ascending flame; and it also partly consists in means for producing a forced draft through the shaft, and of collecting and saving the utilizable or valuable products of combustion or other matters arising from the material acted upon, as hereinafter fully set forth.

Figure 1 of the annexed drawings presents a vertical sectional elevation of a furnace of the described kind, showing the lower part or furnace proper, with the receptacle for the purified material, and a portion of the shaft rising between the two, in the construction of which shaft my invention is partly embodied. Fig. 2 is a vertical sectional elevation of the complete furnace or plant constructed according to my invention, showing the furnace, shaft, and flues, with means for producing forced draft and receptacles for receiving the purified material falling from the shaft, and for collecting and recovering the volatile or utilizable matters from the draft of the shaft.

In Fig. 3 I have shown the complete apparatus as erected with a shaft of the kind shown in my previous application before referred to, and in Fig. 1 I show an enlarged view of the form of shaft which I prefer to use in this case; but either kind may be used in connection with the other features of my invention, as each kind of shaft acts on a similar principle while differing in structure.

The shaft B in Fig. 3 is composed of a series of internal and external cones arranged concentrically, so as to form an annular conically contracting and diverging passage, down through which the granulated material is showered from the top, while flame ascends through the same from the bottom. The several internal and external cones of the shaft, as will be observed, arrest and deflect the falling material at frequent intervals, and compel it to take a rattling zigzag passage alternately converging and diverging, while the flame takes a zigzag reverberating passage in reverse order, so that a most energetic agitation of the falling material and the most effective contact of the flame therewith are produced, which results in the almost perfect consumption or dissipation of the impurities from the ore or other material treated, as will be appreciated. The shaft, as shown in the drawings, rises from a strong foundation, a, to a suitable height—say from fifty to one hundred feet, more or less, according to circumstances.

The conical shaft shown in Fig. 3 is supposed to be formed of cast-iron, the outer portion being supported on the top of the foundation and formed of a series of truncated cones superposed and secured together at their meeting flanges, as indicated. The inner cones are formed in similar sections, which are fixed on a central rod or tube which hangs from a strong cross-bar at the top, and is stepped and supported on the foundation, as illustrated. A shaft of this construction is not readily made in fire-clay or similar fire-proof material, but is more conveniently made of cast-iron, which, however, is not so well suited for some purposes, where the very high heat necessary to purify some substances injuriously affects the structure, whereas for other purposes, where such intense heat is not required, an iron structure is preferable. For this reason I have designed the special form of shaft A shown in Fig. 1, which may be constructed entirely of fire-brick or similar refractory material, and is capable of withstanding any degree of heat necessary in treating any of the usual materials. This shaft rises directly from the foundation, and is preferably made wholly of fire-brick, or fire-brick on the inner courses and common

brick on the outer courses, as will be understood. The flue or passage of the shaft may be either round or square, or of other form in cross-section, as will be understood, the square form being represented in the drawings.

In lieu of the arrangement of cones as in my previous shaft, I employ a series of bars, *r*, extending across the shaft, one above the other at frequent intervals, as illustrated. 5 These bars are of angular or prismatic form in cross-section, arranged with their angles or cones uppermost and their sides inclining to the sides of the shaft, and they are placed successively at right angles or diagonal to each 10 other, or in regular spiral relation, or in other angular positions, as will be understood from Figs. 1 and 2, so that a central vertical section of the shaft, as in Fig. 1, presents in effect a superposed series of cones or pyramids similar to that of Fig. 3, which insures an agitated zigzag rattling passage of the falling ore, &c., and a reverberated passage of the ascending flame, in a manner substantially the same as already described in connection with the conical shaft in Fig. 3. It will be observed, however, that the cross-bars *r* of Figs. 1 and 2 15 may be made of fire-clay, either solid or in the form of tubes, as shown in Fig. 1, in the manner of retorts, and may be firmly supported at either end in the brick-work of the shaft, thus forming a durable, substantial structure capable of resisting the intense heats usual in any metallurgical operation.

Considering now that either form of shaft 20 may be used as occasion demands, I will describe the remainder of the apparatus.

At the base of the shaft is an inclined chute or hopper, *c*, which receives the purified material as it arrives at the bottom of the shaft and 25 discharges it into an accumulating-receptacle, *d*, adjoining one side of the shaft.

e is a curved pipe or flue, which opens upwardly in the base of the shaft and conveys the heat and flame thereto from an ordinary 30 coal-furnace, as in Fig. 1, or from a special form of gas-burner, as in Fig. 3.

The furnace *f* in Fig. 1 may be fed with coal or other solid fuel, and by means of a forced blast an energetic combustion is produced, so as to deliver a great volume of flame or hot gases from the flue *e*, which, rising through the shaft, as before described, purifies the material which may be showered through the same.

55 In Fig. 3 a special form of gas-burner now used connects with the outer end of the flame-flue. In this case *g* indicates a main steam-pipe, from which a branch opens in the form of a jet into a tuyere or injector, *h*, directed into the flame-flue. The outer end of the tuyere is open to admit the inflow of air induced by the steam-jet, as illustrated, and to the tuyere also connects a hydrocarbon gas or oil pipe, *i*, which allows a regulated inflow of combustible gas 60 or oil, together with the air, as will be understood. Hence, when the burner is in operation, the steam, air, and hydrocarbon mingle, pass

through the flue *e*, and rise in the shaft in voluminous tongues of flame. Air may be admitted at the base of the shaft through suitable openings, as seen in Fig. 1, if required to render the combustion in the shaft more perfect.

The top of the shaft is surmounted by a hopper or receptacle, *k*, into which the pulverized ore, bone-black, or other material is fed, the material being conveyed thereto by suitable elevators or other means, as will be understood. The neck of the hopper opens into the top of the shaft, and the material is fed from the same by a shaking or sifting device, *l*, operated by a suitable motor from the base of the apparatus, so as to feed the material regularly in a distributed shower down through the shaft.

At the discharging end of the chute *c* in 85 the receptacle is arranged an air-blast nozzle, *m*, which delivers a strong jet of cold air against the entering stream of purified ore or other material, which is presumed to issue from the chute in a red-hot condition, so that this 90 air-jet serves to burn out the remnant of impurities that may have escaped dissipation in the shaft, and at the same time cools down the heated material preparatory to its removal. The purified material is removed from the receptacle through the door *n*, and the hot air escapes therefrom through the flue *o*. The draft of the shaft is conveyed through a large descending flue, *s*, opening from the top of the shaft and dipping at its lower end into a water-box or condensing-chamber, *p*, so that its mouth opens slightly below the level of the fluid therein, or just on a level therewith, as illustrated, this level being kept constant by a supply of water and a regulating float-valve, as will be 95 understood.

From the main steam-pipe *g* a branch extends into the descending flue and terminates in an outwardly-directed jet or nozzle, *t*, from which a strong steam-jet is emitted, which produces by induction a powerful current in the flue, which withdraws the draft from the shaft and forces the air, gases, and dust or ashes through the water or other liquid in the chamber. It will hence be seen that valuable metallic dust or other solid matter suspended in the draft will be arrested by the water and deposited therein, thus enabling the same to be recovered when required, while the soluble or condensable vapors or gases will be absorbed 110 or dissolved by the water or other fluid, which may, after it is sufficiently charged, be drawn off and thus utilized. In treating sulphurous ores this water will possess a sulphurous or sulphuric character, and may be utilized as 115 sulphurous or sulphuric acid after appropriate treatment, while gold or other metallic dust may be recovered from the precipitate in the vessel. Hence not only are valuable products thus obtained from the draft of the shaft which 120 would otherwise be wasted, but irritating or poisonous matters are arrested and prevented from polluting the surrounding air.

From the top of the chamber *p* a high ver-

tical flue rises and opens at the top into the atmosphere, and thus serves to carry off the fixed or useless gases after their passage through the water in the condensing-chamber, and at 5 the same time assists the draft or action of the jet *t*, as will be understood.

It will therefore be seen that by these combined improvements I produce a very complete apparatus for the described purposes, which 10 not only embodies a substantial and durable fire-proof structure of the shaft and means for energetically agitating the falling ore and subjecting it to the action of flame in the most efficient manner, but also includes means for producing a powerful forced draft through the shaft, and for arresting and recovering the 15 utilizable matters therefrom, which renders my apparatus an important improvement in this line.

20 I do not here claim the conical form of shaft shown in Fig. 2, as the same is claimed in my former application before referred to. Neither do I broadly claim a water-box or condensing-chamber in connection with descending and 25 ascending flues.

I am also aware that ore-shafts have been formed with angular bars extending across the same; but in such cases the bars have been arranged in parallel order, one above the other, 30 and in several vertical lines or rows side by side, whereas I employ but one vertical line or series of overlying bars, which are placed at

various angles to each other or in spiral order, whereby I secure a better result with a much simpler construction.

35

What I claim is—

1. A roasting-furnace having a shaft formed with a series of bars extending across its passage, with their sides inclined to the axis of the shaft and arranged one above the other at 40 various angles in spiral order, substantially as and for the purpose set forth.

2. In a roasting-furnace, a shaft provided with a series of hollow bars permanently built into it, said hollow bars having inclined upper 45 and lower surfaces and arranged one above the other in spiral order, substantially as and for the purpose specified.

3. The combination, with the shaft *A*, provided with air-passages *v*, the furnace *f*, and the receptacle *d*, located at opposite sides of said shaft, of the chute *C*, having its upper end of substantially the same size as the interior of the shaft, and the blast-pipe *e*, extending into the shaft through the center of the chute 55 *C*, the lower ends of the pipe *e* and chute *C* extending through opposite walls of the shaft and entering respectively the furnace *f* and the receptacle *d*, substantially as shown and described.

JOHN CAMPBELL.
